COMBINED TRAVEL CLOCK AND CASE

Klaus Kroner, Magstadt, Wurttemberg-Baden, Germany,
assignor to Blessing-Werke KG., Waldkirch im Breis-
gau, Germany

Filed Aug. 24, 1972, Ser. No. 283,509

Claims priority, application Germany Feb. 25, 1972

Term of patent 14 years

Int. Cl. D10—01

U.S. Cl. D10—18

FIG. 1

FIG. 4

FIG. 5

FIG. 2

FIG. 3

FIG. 6

FIG. 7

FIG. 8

FIG. 9

FIG. 10

FIG. 11

FIG. 12

FIG. 1 is a top view of a combined travel clock and case showing my new design;
 FIG. 2 is a front elevational view thereof;
 FIG. 3 is a side elevational view thereof;
 FIG. 4 is a top plan view thereof in the open position;
 FIG. 5 is a front elevational view of FIG. 4;
 FIG. 6 is a left side elevational view of FIG. 4;
 FIG. 7 is a top plan view of FIG. 4 with the clock swung out of the case;
 FIG. 8 is a front elevational view of FIG. 7;
 FIG. 9 is a left side elevational view of FIG. 7;
 FIG. 10 is a perspective view showing the case in upright position with the clock swung out of the case;
 FIG. 11 is a perspective view showing the case in horizontal position with the clock swung out of the case; and
 FIG. 12 is a front perspective view of FIG. 1.

I claim:
 The ornamental design for a combined travel clock and case, substantially as shown.
